UNITED STATES PATENT OFFICE.

ALBERT F. PRESTON, OF BOSTON, MASSACHUSETTS, ASSIGNOR TO THE
PRESTON MACHINE COMPANY, OF SAME PLACE.

MACHINE FOR STRETCHING UPPERS.

SPECIFICATION forming part of Letters Patent No. 350,467, dated October 5, 1886.

Application filed February 15, 1886. Serial No. 192,000. (No model.)

To all whom it may concern:

Be it known that I, ALBERT F. PRESTON, of Boston, county of Suffolk, and State of Massachusetts, have invented an Improvement in 5 Machines for Stretching Uppers, of which the following description, in connection with the accompanying drawings, is a specification, like letters on the drawings representing like parts.

10 The object of this invention is to construct a machine for shaping the uppers of boots and shoes at the shank portion preparatory to lasting the same, to facilitate the lasting operation, and to insure a better fit of the boot or 15 shoe about the shank portion of the foot of the wearer.

In accordance with this invention a clamp or pair of jaws is provided to grasp and hold the upper a short distance from its edge, and 20 a series of grippers arranged diagonally with relation to each other, but in the same horizontal plane, are employed to grasp the edge of the upper, said grippers being constructed and arranged to be moved in the same horizontal plane, but diagonally with relation to 25 each other, to pull and stretch the upper at the shank portion as it is held by the upper-holding clamp. A series of hammers are also provided, which automatically rise as the 30 grippers are drawn backward from the upper-holding jaw, and which are tripped to strike the upper near its edge at the limit of the backward movement of the grippers, the upper at this time being stretched to the desired 35 extent, thereby giving to the upper while stretched a "permanent set."

The invention consists, essentially, of an upper-holding clamp or jaw to grasp the upper a short distance from its edge, combined with 40 a series of diagonally-arranged grippers to grasp the edge of the upper, and means, substantially as will be described, for moving said grippers diagonally with relation to each other, but in the same horizontal plane, to there- 45 by stretch or shape the upper at a given point; also, of an upper-holding clamp or jaw to grasp the upper a short distance from its edge, a series of diagonally-arranged grippers to grasp the edge of the upper, and means, substan- 50 tially as will be described, for moving said grippers diagonally with relation to each oth-

er, but in the same horizontal plane, combined with a series of hammers to strike the face of the upper when the grippers arrive at their extreme rearward position, to thereby give to the upper a permanent set, substantially as will be described.

Figure 1 represents in side elevation a machine for stretching the uppers of boots and shoes and constructed in accordance with this 60 invention; Fig. 2, a top or plan view thereof; Fig. 3, a longitudinal section of Fig. 2, taken on the dotted line *xx*; Fig. 4, a cross-section of Fig. 3, taken on the dotted line *yy*; and Fig. 5, an under side view of Fig. 2.

The base-plate A, upright or standard B, and frame-work or head C are all of suitable construction to support the working parts of the machine.

The shank portion of the upper to be stretched 70 by the machine herein to be described is clamped at a point a short distance from its edge by a pair of jaws, *a* *a'*, preferably having yielding bearing-surfaces *a*², to prevent marring the leather; or it may be a yielding top 75 surface and a corrugated bottom surface. The upper-jaw, *a'*, having a curved shank, as shown at *a'*, to overhang the parts which operate upon the surface of the material at the edge, is attached to a slide-bar, *a*⁸, moving upon the 80 top or bed plate, D, of the machine, said slide-bar being normally retained in its forward position by springs *a*⁹ *a*⁹, connected to each side therefor and to the bed-plate D. A stud or pin, 2, projects from the upper side of the slide-bar *a*⁸, which, when the springs *a*⁹ *a*⁹ are retracted, strikes against a cross-bar, *e*, extending across the rear portion of the head of the machine, thereby limiting the forward movement of the said slide-bar. The extreme 85 rear side of the slide-bar is connected to an arm, *c*, projecting from a rock-shaft, *d*, by a link, *a*¹⁰, so that as said rock-shaft *d* is rotated the slide-bar *a*⁸ and its attached jaw *a'* are reciprocated. The bed-plate D is provided with 90 an elongated slot or recess, 25, at a point beneath the slide-bar *a*⁸, to permit the passage of a downwardly-extended arm, *b*, attached to the said slide-bar. The lower jaw, *a*, having a suitably-extended shank, *a*³, passing beneath 95 the bed-plate D of the head of the machine, is pivoted to the downwardly-extended arm *b* 100

by a pin, a^4 , so that as the slide-bar reciprocates the lower jaw, a , is carried with it. The extreme end of the shank a^3 of the lower jaw, a , is connected to a treadle, E, by a rod, a^5 , depression of the treadle E causing the lower jaw, a , to rise against the tension of the retracting-spring a^6 . The arm c of the rock-shaft is also connected with said treadle E by a connecting-rod, e' , thereby insuring a simultaneous sliding and clamping movement of the pair of jaws a a' . Suitable friction-rolls, e^2 , turn upon journals extending from each side of the arm b at its lower end, which rolls bear upon the under side of the bed-plate D. The grippers which grasp the edge of the upper (herein shown as four in number) are located two upon each side of the jaws a a' , and consist of a lower jaw, f , pivoted to a slide-bar, f' , which latter serves as the upper jaw and bears upon the top of the bed-plate D. The said sliding jaws f' are each arranged diagonally with relation to the other, or fan-like, as shown best in Fig. 2, so that the pair of grippers upon each side of the jaws a a' will pull upon the upper in lines radiating from a common center, which radial lines pass through the biting-faces of the jaws a a' , as designated by the dotted lines, Fig. 2, previous to converging. The lower jaws, f , of the grippers, pivoted to the sliding jaws f' by pins 5, are each provided with an upwardly-extending arm, f^6 , which latter are connected by links f^7 to arms f^8 , attached to the rock-shaft d. The rock-shaft d is hung and adapted to be rocked in brackets d' , extended from the bed-plate D. As the rock-shaft d is rotated, the arms f^8 first cause the pivoted jaws f to grip the material, and as the rock-shaft is further rotated the sliding jaws f' are caused to move rearwardly from the holding-jaws a a' , and diagonally with relation to each other, but in the same horizontal plane. The sliding jaws f' are guided in their passage by recesses cut in the under side of the cross-bars e and e^5 , through which the said jaws pass, the said cross-bars e e^5 being bolted to the bed-plate D by any suitable bolts. The sliding jaws are each provided with suitable stops or pins, 3 4, which are located so as to strike against opposite sides of the cross-bar e, limiting the backward and forward movement of the said jaw, and to facilitate the passage of the said jaws f f' to and fro. Suitable friction-rolls, f^2 , are provided, which rotate upon pivots f^3 , passing downward through the cross-bar e^5 . The diagonally-arranged grippers are each of suitable length, so that in their normal position their biting-faces lie in a line substantially parallel with the holding-jaws a a' , so that they may all grip simultaneously the edge of the material, which is usually straight. These grippers are each independently connected to an arm attached to the rock-shaft d, which is also parallel with the biting-faces of the grippers while in their normal positions, and by the diagonal or fan-like arrangement of the grippers, as described, the rock-shaft, as it is ro-

tated, causes the grippers to be moved rearwardly, their biting-faces gradually assuming a position in the arc of a circle; and it will be seen that the material held by the jaws a a' will be pulled or stretched radially by the grippers from a common center, as shown by the dotted lines, Fig. 2, before referred to, the jaws a a' , holding the upper, being interposed within the path of such radial lines. The arc of a circle thus formed by the grippers may be varied by varying the length of the slide-jaws f' . The upper having been grasped by the jaws a a' and stretched to the desired extent 80 by the grippers f f' , it has been found desirable to give to it, while held in such condition, a permanent set, thereby obviating the necessity of stretching the same sufficiently to compensate for the elasticity of the leather when 85 released. This I have accomplished, in this instance, by a series of hammers, n, (shown as three in number and located alternately with the grippers,) the said hammers having rearwardly-extended shanks n^1 , which are connected together by cross-pieces m, (shown as broken off in Fig. 2,) thus forming a frame carrying the hammers, which is pivoted or hinged to the cross-bar e, that it may rise or fall. The hammers n normally bear upon anvil-pieces n^2 , (see Fig. 5,) which project sufficiently from the bed-plate D, to which they are attached, that they will lie in line with the grippers when the latter are in their extreme rearward position. Cam-blocks n^3 are attached to opposite sides of the two interior sliding jaws, f' , while suitable fingers, n^4 , are pivoted to the frame carrying the hammers n, so that as the sliding jaws f' are moved backward the cam-blocks n^3 , bearing against the finger n^4 , cause the frame carrying the hammers to rise. The cam-block n^3 is of such length that when the sliding jaw f' arrives at its extreme rearward position the finger n^4 passes over the same, permitting the hammers 105 to fall upon the surface of the material, thereby giving to the said material a permanent set. The sliding jaw f' then returning to its normal position, the finger n^4 , which is pivoted, recedes over the cam-block n^3 . The rock-shaft 110 d, rotated by the treadle E, as described, is returned to its normal position by suitable springs, d^10 , attached to the said rock-shaft near each end and to the frame-work C.

The entire operation may be briefly stated 120 as follows: The operator, placing an upper between the jaws a a' , and sufficiently far to enter the grippers, depresses the treadle E, when the jaws a a' and grippers will grip the material, the jaws a a' receding slightly. As the 125 treadle is further depressed, the diagonally-arranged grippers are moved backward, and the jaws a a' , while holding the upper, are also moved backward, but to a somewhat less extent, only sufficient to prevent the leather being torn. During this backward movement the hammers are automatically raised, as described. When the grippers arrive at their 130 extreme rearward position, the hammers fall

and permanently set the material, and the treadle E is then released, that the upper may be removed.

By the machine herein described an upper 5 (previously soaked to render the same pliable) is stretched at the shank portion sufficiently in the arc of a circle about a definite point, as described, to permit the same to be lasted with facility, and also to insure a better fit of 10 the shoe, and by the arrangement of the grippers the usual seam at the shank portion is not ripped, as the inside grippers pull upon the upper on the interior radial lines, and by the construction of the grippers herein de- 15 scribed, while firmly holding the leather, they do not mar or abrade the same in any way.

It is obvious that, if desired, the link a^{10} may be omitted and weak springs a^9 employed, in which case the upper-holding jaws $a\ a'$ will be 20 moved back as the upper is pulled by the grippers.

The rods $e\ a^6$ may, if desired, be connected with any suitable power-driven motor without departing from this invention.

25 I claim—

1. In a machine for stretching the upper of a boot or shoe, the movable clamp to grasp and hold the upper at a point some distance from its edge, combined with a series of grippers to grip the upper at the edge, and means, substantially as described, for moving both the upper-holding clamp and grippers rearwardly, but for different distances, substantially as described.

35 2. In a machine for stretching the upper of a boot or shoe, the clamp to grasp and hold the upper at a point some distance from its edge, combined with a series of grippers arranged diagonally with relation to each other, as described, to grip the upper at the edge, and means, substantially as described, for simultaneously moving both the upper-holding clamp and grippers rearwardly, but for different respective distances, all as set forth.

45 3. In a machine for stretching the upper of a boot or shoe, the movable clamp to grasp and hold the upper at a point some distance from its edge, the series of diagonally-moving grippers to grasp the upper at the edge, and means, substantially as described, for simultaneously moving the said upper-holding clamp and grippers rearwardly, but for different respective distances, combined with a series of hammers constructed and arranged, substantially as described, to beat the said upper when the grippers are in their rearward position, all substantially as and for the purpose set forth.

4. In a machine for stretching the upper of a boot or shoe, the sliding jaw a' and pivoted 60 jaw a , the diagonally-arranged sliding jaws f' , and pivoted jaw f , combined with rock-shafts, arms projecting therefrom in different directions, link a^{10} , and rods f^7 , respectively connecting the upper-holding jaws $a\ a'$ and the 65 jaws $f\ f'$ with said arms, and means, substantially as described, for operating said rock-shaft, all substantially as described.

5. In a machine for stretching the upper of a boot or shoe, the upper-holding clamp $a\ a'$ 70 and grippers $f\ f'$, and means, substantially as described, for moving them, combined with a series of hammers, and means, substantially as described, for automatically raising and dropping said hammers as the grippers are 75 moved, and the anvil-blocks n^2 , all substantially as described.

6. In a machine for stretching the upper of a boot or shoe, the upper-holding clamp $a\ a'$, the grippers consisting of the pivoted jaw f' 80 and the sliding jaw f , said grippers being arranged diagonally, as described, and being of varying lengths, whereby the acting faces of the grippers may lie in a line substantially parallel with the upper-holding clamp in their 85 normal position, but to gradually assume an arc of a circle as they are moved, combined with a rock-shaft, and means, substantially as described, connecting said grippers with the rock-shaft, whereby they are simultaneously 90 moved, all substantially as described.

7. In a machine for stretching the upper of a boot or shoe, the yielding or movable clamp to grasp and hold the upper at a point some 95 distance from its edge, combined with a series of grippers to grip the upper at the edge, and means, substantially as described, for moving said grippers rearwardly, substantially as described.

8. In a machine for stretching the upper of a boot or shoe, the yielding or movable clamp to grasp and hold the upper at a point some distance from its edge, combined with a series of grippers arranged diagonally with relation to each other, as described, to grip the upper 105 at the edge, and means, substantially as described, for moving said grippers rearwardly, all as set forth.

In testimony whereof I have signed my name to this specification in the presence of two sub- 110 scribing witnesses.

ALBERT F. PRESTON.
